(57) **CLAIM**

The ornamental design for a toy shield assembly, as shown and described.

DESCRIPTION

FIG. 1 is a perspective view of the toy shield assembly of the instant invention;

FIG. 2 is a front elevation view thereof;

FIG. 3 is a rear elevation view thereof;

FIG. 4 is a right side elevational view thereof;

FIG. 5 is a left side elevational view thereof;

FIG. 6 is a top end view thereof; and,

FIG. 7 is a bottom end view thereof.

The broken lines represent portions of the design that form no part of the claim.
